OF MINNESOTA

CLOSED-BACK TOWEL STAND

Application filed March 28, 1927. Serial No. 179,082.

Our invention relates to towel cabinets of the stand or floor type adapted to rest upon the floor of the wash room or other place where the cabinet may be located or in a 5 recess or space formed in the wall of such room, and the primary object of our invention is to provide a cabinet of this type so constructed that the clean supply of towel may be inserted at the front of the cabinet 10 and the soiled towel removed by the attendant standing in the same position in front of the cabinet. It is, therefore, not necessary to provide an opening in the rear wall of the cabinet through which access may be had 15 to the interior or to move the cabinet away from the upright wall against which it may be placed, the loading and unloading operation being performed entirely through the front of the cabinet.

20 A further object is to provide a cabinet which can be arranged or mounted within a recess in an upright wall with the front of the cabinet flush substantially with the surface of the wall, a decided advantage in 25 wash rooms where there is comparatively little space for a cabinet to stand out on the floor of the room.

Other objects of the invention will appear from the following detailed description. 30 The invention consists generally in various constructions and combinations all as hereinafter described and particularly pointed out in the claims.

In the accompanying drawings forming a 35 part of this specification

Figure 1 is a vertical sectional view through a towel cabinet embodying our invention;

40 Figure 2 is a view of a similar cabinet ready for use and arranged within a recess in the wall of the room where the cabinet is placed;

45 Figure 3 is a perspective view of a towel holder or cabinet that is adapted to fit into a wall recess without extending to the floor of the room;

Figure 4 is a transverse sectional view on the line 4—4 of Figure 5;

50 Figure 5 is a vertical sectional view show-

ing the holder or cabinet of Figure 3 mounted within the wall recess; and

Figure 6 is a front elevation showing the appearance of the cabinet or holder to a person in the room where it is located. 55

In the drawing, 2 represents the side walls of a floor cabinet, 3 the bottom thereof having suitable supporting legs, 4; 5 the closed back of the cabinet and 6 a front panel or wall which covers the lower portion of the 60 cabinet and conceals the depending soiled web of towel therein. The top of the cabinet has a closed wall 7 with the usual mirror 8 at the front beneath which is an opening 9. In the rear of this opening, we provide 65 a shelf 10 adapted to support the supply of clean towel 11 placed loosely on this shelf and preferably we provide a shelf 12 above the supply of clean towel, the forward edge of the shelf forming a guide for contact with 70 the clean towel web, that is stretched from the supply 11 to a delivery feed roll 13, mounted in the side walls of the cabinet above the shelf 12 and having a suitable roughened surface which will adhere to the web of clean 75 towel. A gate 14 is hinged at 15 to the shelf 10 and the hinges are preferably provided with springs 16 which normally tend to hold the gate in an upright position in contact with the forward edge of the shelf 12, the 80 pressure of the gate on the web serving to smooth out the wrinkles and straighten any folds that may be formed therein before the web reaches the feed roll 13. The upper edge of the gate preferably has a flanged 85 portion 17, the forward edge of which is substantially flush with the corresponding edges of the side walls of the cabinet as shown in Figure 1 and this flange has a folded forward portion on which the web of 90 clean towel is adapted to slide and depend in position to be grasped and pulled by the user. The dotted lines in Figure 1 indicate substantially the position which the clean 95 web of towel assumes when it is pulled outwardly to a using position. When the gate 14 is in its normal working position, it will be substantially vertical and will conceal the clean towel supply and preferably we provide a lock 18 of suitable construction for 100

holding the gate 14 in its closed position and preventing any mischievous or unauthorized person from having access to the towel supply. The attendant, of course, will have a key to this lock and in loading the cabinet will release the gate and swing it to the dotted line position of Figure 1 when the clean towel supply can be conveniently placed on the shelf and the clean web 10 stretched over the feed roll 13. Below the shelf 10, we prefer to provide guides 19 in the side walls of the cabinet to receive a take up roll 20 on which the web of soiled towel is wound and adjacent these guides we mount 15 a second feed roll 21 also having a roughened surface and a driving connection, such as the sprocket chain 22, with the feed roll 13, so that movement of these rolls will be simultaneous and as they are preferably of the same size their peripheral speed will be the same and when the clean web of towel is pulled down by the user, a corresponding length thereof will be wound on the take up roll 20 through the frictional engagement 25 thereof with the surface of the roll 21. Preferably a tension roll 23 is mounted in the side walls of the cabinet below the feed roll 21 which serves to guide the web of soiled towel and smooth out any wrinkles or folds 30 that may have been formed therein. Notches 24 are preferably provided in the guides 19 to receive the bearings of the take up roll 20 when the soiled towel has been removed 35 and preparatory to winding the end of another web thereon in loading the cabinet. In Figure 2, the wall 25 of the building is shown provided with a vertical recess 26 extending down to the floor and of suitable depth to receive the cabinet so that the front 40 thereof will be flush substantially with the wall of the room and thus the cabinet is adapted for use in wash rooms where the space is limited and generally the recess will be formed in the wall when the building is 45 built, being made of suitable dimensions to receive the cabinet. The wall in an old building can, of course, be recessed for the insertion of the cabinet if desired. In Figure 3, we have shown a holder having side walls 27 corresponding to those of the cabinet described except that they are shorter and open at the top and bottom. Spacing strips 28 are provided on each side to close the gaps between the side walls and the walls 50 of the recess and provide sufficient space for the operation of the driving connection 22 between the feed rolls. These side walls 27 are supported in the side walls of the recess as indicated in Figures 5 and 6, the recess 55 being similar to the one shown in Figure 2 except that it does not extend down to the floor of the room. We will designate the recess, therefore, by the same reference numeral with the addition of the exponent a. 60 The interior arrangement of the cabinet

shown in Figures 3 to 6 is substantially the same as described with reference to the previous figures and we will indicate the parts by the same reference numerals. In all of these cabinets, the attendant having unlocked the gate at the front of the cabinet, may insert the supply of clean towel at the front and having removed the soiled roll can easily and conveniently stretch the clean web over the upper feed roll and from thence 70 downwardly to the take up roll all while standing in front of the cabinet and without the necessity of moving the cabinet away from the wall or having access through the rear wall thereof for any purpose. The construction, therefore, simplifies the manufacture of the cabinet and enables the attendant to save considerable time in the operation of filling the cabinet with a clean supply of towel and removing the soiled portion. A 75 further advantage lies in the fact that either form of cabinet can be inserted into a recess in the wall where it will be inconspicuous and will not occupy space on the floor of the wash room which might be desired for other 80 purposes. Whenever desired, either form of cabinet may be removed from the recess for examination or repairs or for any other purpose. Either form of cabinet may be made of metal, wood, or any other suitable material that may be found best adapted for the 85 purpose.

We claim as our invention:

1. A towel cabinet having a closed back and an open front, and adapted to receive 100 a supply of clean towel placed in said cabinet through said open front, said cabinet having an opening in its upper portion and a lower projecting portion, a delivery feed roll mounted in said cabinet above said 105 towel supply, whereby a web of clean towel may be stretched to contact with said feed roll and depend therefrom into said projecting lower portion and being in position to be grasped and pulled by the user, a take 110 up roll below the towel supply inserted into and removed from the cabinet through said open front and whereon the loose end of the towel web may be wound, a tension roll in 115 the front of and below the take up roll and a take up feed roll having a driving connection with said first named roll and a surface to contact with the towel web on said take up roll and revolve said take up roll synchronously but in the opposite direction 120 from the movement of said delivery feed roll.

2. A towel cabinet having an open front, and adapted to receive a supply of clean towel, a delivery feed roll to which a web 125 of clean towel may be stretched for delivery to the user, the front of the cabinet having an opening in its upper portion through which the user may have access to the web of clean towel, a gate normally 130

closing said opening in front of the towel supply, and having a locking means to prevent access to the towel supply, a shelf above which said gate extends, the front edge of said shelf forming a guide for the towel whereby a web of clean towel may depend from said delivery feed roll and contact with said gate on its outer side in position to be pulled by the user, a take up feed roll having a driving connection with said delivery feed roll and a take up roll accessible through the open front of the cabinet for insertion and removal at the front and whereto the web of towel may be stretched through said open front below said gate and wound on said take up roll for contact with said take up feed roll.

3. A towel cabinet having an open front, a shelf in the upper part of the cabinet adapted to hold a web of clean towel thereon, a second shelf above said first shelf, a delivery feed roll mounted in the cabinet above said second shelf and whereto a web of clean towel may be stretched in contact with the forward edge of said second shelf, a gate hinged in front of said towel supply and adapted to press the web of clean towel against the edge of said second shelf and when open allow access to the towel supply, the construction being such that said web may depend from said feed roll in front of said gate in position to be grasped by the user, the front of the cabinet being open to allow access of the towel user to said web, a take up feed roll mounted below the first mentioned shelf and having a driving connection with the delivery feed roll and a take up roll accessible through the open front of the cabinet for insertion and removal and whereon the loose end of the towel web may be wound for contact with said take up feed roll.

4. A towel cabinet comprising a back, a shelf in the upper part of the cabinet, and a door hinged to said shelf, a delivery feed roll in the upper part of the cabinet, the lower portion of the cabinet extending forwardly of said door, a tension roll in the projecting lower portion of the cabinet, and a soiled towel roll above and to the rear of the tension roll having a feed roll below the soiled towel roll geared to the delivery roll in the top of the cabinet whereby, by opening the door in the front of the cabinet, a supply of clean towel can be placed upon the said shelf and the towel be stretched upwardly over the upper delivery roll and the toweling may hang in front of the door and straight down into the projecting lower portion and below said tension roll, thence pass upwardly to the soiled towel roll, and a pull on the towel to draw it to wiping position will turn the upper delivery roll but the soiled towel roll will be held from turning

to deliver the soiled portion of the towel to the front of the cabinet.

5. A towel cabinet having a fixed shelf therein for holding a supply of clean toweling, a door extending upwardly in front of said shelf and terminating short of the top wall of said cabinet, instrumentalities mounting said door for swinging movement on said cabinet, the upper edge of said door being provided with means for contacting with and directing toweling downwardly in front of and spaced from said door into position of use.

In witness whereof, we have hereunto set our hands this 24th day of March, 1927.

FRANK M. STEINER.
GOTTFRID OLSON.
